UNITED STATES PATENT OFFICE.

VICTOR SINCOVITZ, OF PUEBLO, COLORADO.

AUTOMATIC RAIL FEED.

1,408,411.

Specification of Letters Patent. Patented Feb. 28, 1922.

Application filed March 9, 1921. Serial No. 450,914.

To all whom it may concern:

Be it known that I, VICTOR SINCOVITZ, a citizen of the United States, residing at the city of Pueblo and county of Pueblo and

5 State of Colorado, have invented certain new and useful Improvements in Automatic Rail Feeds; and I do declare the following to be a full, clear, and exact description of the invention, such as will enable others 10 skilled in the art to which it appertains to make and use the same, reference being had to the accompanying drawings, and to the characters of reference marked thereon, which form a part of this specification.

15 The object of this invention is to provide efficient automatic means for feeding rails to cutting devices whereby the rails are cut into short sections.

Briefly, the invention comprises a series 20 of live rolls by means of which each rail is fed individually to the cutting device. The forward end of the rail is adapted to engage a trip plate to lift the same for the purpose of setting a pawl on a ratchet, the weight of 25 the trip plate being sufficient, when disengaged by the rear end of the rail, to rotate the ratchet when said plate drops and thereby rotate a series of rail-feeding sprockets capable of feeding one rail at a time to the 30 live rolls.

In the drawings:

Fig. 1 is an end elevation showing the application of the invention;

Fig. 2 is a front elevation as indicated by 35 line 2—2 of Fig. 1;

Fig. 3 is a fragmentary horizontal detail indicated by the line 3 of Fig. 2;

Fig. 4 is an elevation of one of the rail-feeding sprockets as indicated by line 4 of 40 Fig. 3;

Fig. 5 is an enlarged detail indicated by the arrow 5 of Fig. 2, showing a trip plate in plan; and

Fig. 6 is a side elevation of the trip plate 45 as indicated by the line 6—6 of Fig. 5.

A plurality of standards 10 support a plurality of inclined rail-receiving slides 12 upon which the rails to be handled are placed.

A small stop 14 is provided adjacent the 50 lower end of each of the slides 12 to limit the sliding motion of said rails, due to gravity. A row of short standards 15 are provided in the front of the device and spaced from the forward standards 10, a plurality 55 of cross bars 16 extending between the front standards 10 and said standards 15. Rail-

guiding members 18 are connected with said cross bars 16 and the forward end of the slides 12, the forward portions of said guides 18 being inclined as shown, for the 60 purpose of conducting a rail as it is fed forward onto a plurality of live rolls 20 which are driven by means of a line shaft 22 and beveled gears 24 having a driving connection with the shafts 25 of the rolls 20.

A plurality of rail-feeding sprocket wheels 30 are fixedly mounted on a longitudinally-extending shaft 32 journaled in bearings 34 carried by said cross bars 16. The sprockets 30 are so arranged that the 70 teeth thereof will engage under the rail engaging the stops 14 to lift the same therefrom as the sprockets 30 are rotated, so as to support the rail upon the sprockets as indicated. The sprockets are rotated step 75 by step so that a rail is lifted from the slides 12 at each step and a rail is discharged from said sprockets to the live rolls 20 at each step. The rail shown in dotted lines in Fig. 1 is in the position when just discharged 80 from the sprockets 30 onto the guides 18.

For the purpose of rotating the sprocket wheels 30 to feed the rails, a ratchet 35 is fixedly secured to said shaft 32 at a point in the direction of feed of the rails and beyond 85 their position as fed from the sprockets. The bearings 36 on the ends of arms 38 are journaled on said shaft 32, the forward ends of said arms 38 carrying a heavy trip plate 40 whose face is inclined on an angle as indicated in the various views, the position of the plate being at an angle to the vertical and also at an angle to the horizontal. The lower end of the plate, which is also its forward end, has a roller 42 mounted on a shaft 95 44 carried in journaling ears 45 of said plate 40. The back or upper side of the plate is provided with an integral re-enforcing rib 46 which also provides means for connection of the various arms 38. If desired, the arms 100 38 and plate 40 may be cast in one heavy piece. The middle one of the arms 38 is divided, as shown in Figs. 5 and 6, and is provided with journals 48 to receive a pivoting pin 50 by means of which a pawl 52 105 is pivoted on said arm. The free end of the pawl 52 is provided with an engaging tooth 54 adapted to engage the teeth of the ratchet wheel 35 for rotation of the latter.

In operation, the rail is fed by the live 110 rolls 20 in the direction of the arrow in Fig. 5, the end of the rail being forced

against the inclined lower face of the plate 40 whereby the continued motion of the rail against said face causes the plate 40 to be lifted, the arms 38 swinging on the shaft 32 as a pivot. When the lifting movement of the plate 40 reaches its maximum, the rail R passes under the roller 42 and travels thereunder until carried past the plate 40 and roller 42. When said arms 38 and trip 10 plate 40 are elevated, as just described, the tooth 54 of the pawl 52 is caused to be moved rearwardly on the ratchet 35 to engage one tooth farther back. When the rail R leaves the roller 42, the plate 40 drops, the weight 15 of said plate and its arms 38 being sufficient to cause the drop and to rotate the ratchet 35 together with the shaft 32 and the sprocket wheels 30 so as to feed one rail onto the guides 18 and thence to the live rolls 20 20 and to lift another rail which engages the stops 14 from the slides 12.

From the foregoing it will be seen that I have provided comparatively simple and automatic means for feeding one rail from 25 a pile and onto a series of live rolls as rapidly as a rail is fed forward by said live rolls.

I claim:

1. A rail feed comprising a trip adapted 30 to be moved by a moving rail, and means operable by said trip to feed a rail.

2. A rail feed comprising a trip adapted to be moved by a moving rail, means to move the rail, and means operable by the trip 35 to feed another rail to said moving means after passage of the first rail.

3. A rail feed comprising means to move a rail longitudinally, a trip adjacent said means adapted to be moved by a moving rail, 40 means for supplying rails, and rail-feeding means operable by said trip to take a rail from said supplying means and to feed a rail to said moving means.

4. A rail feed comprising means to move 45 a rail longitudinally, a weighted trip adjacent said means adapted to be lifted by the advancing end of a moving rail, and rail-feeding means operable by said trip when it falls after disengagement by said 50 moving rail to feed a rail to said moving means.

5. A rail feed comprising means to move a rail longitudinally, a weighted trip adjacent said means adapted to be lifted by the advancing end of a moving rail, and rail-feeding means operable by said trip when it falls after disengagement by said moving rail to feed a rail to said moving means, said rail-feeding means also being operable by said trip to take a rail from a rail supply. 60

6. A rail feed comprising means to move a rail longitudinally, a weighted trip adjacent said means adapted to be lifted by the advancing end of a moving rail, and rail-feeding means operable by said trip 65 when it falls after disengagement by said moving rail to feed a rail to said moving means, said rail-feeding means comprising a rotary sprocket wheel whose teeth are adapted to engage, support and move a rail. 70

7. A rail feed comprising means to move a rail, a weighted trip adjacent said moving means adapted to be lifted by a moving rail, and rail-feeding means operable by said trip when it falls after disengagement by 75 the moving rail to feed another rail to said moving means.

8. A rail feed comprising means to move a rail, a weighted trip adjacent said moving means adapted to be lifted by a moving rail, and rail-feeding means operable by said trip when it falls after disengagement by the moving rail to feed another rail to said moving means, said rail-feeding means comprising a rotary sprocket wheel whose teeth 85 are adapted to engage, support and move a rail. 90

9. A rail feed comprising means to move a rail, a weighted trip adjacent said moving means adapted to be lifted by a moving rail, rail-feeding means operable by said trip when it falls after disengagement by the moving rail to feed another rail to said moving means, said rail-feeding means comprising a rotary sprocket wheel whose teeth 95 are adapted to engage, support and move a rail, a ratchet to turn said sprocket wheel, and a pawl on the trip engaging the ratchet and movable by the trip when lifted to engage another tooth. 100

In testimony whereof I affix my signature.
VICTOR SINCOVITZ
